CLAIM

We claim, the ornamental design for a vehicle charger, as shown and described.

DESCRIPTION

FIG. 1 is a perspective view of a first embodiment the invention;

FIG. 2 is a front view of the embodiment of FIG. 1;

FIG. 3 is a rear view of the embodiment of FIG. 1;

FIG. 4 is a side view of the embodiment of FIG. 1, the opposite side being a mirror image thereof;

FIG. 5 is a top view of the embodiment of FIG. 1; and,

FIG. 6 is a bottom view of the embodiment of FIG. 1.

The broken lines shown in FIG. 1-FIG. 6 are environmental and not part of the claimed design.

1 Claim, 5 Drawing Sheets
